DESIGN FOR A BATHING CAP

Frank Brighten, London, England

Application May 26, 1936, Serial No. 62,851
In Great Britain March 11, 1936

Term of patent 14 years

To all whom it may concern:

Be it known that I, Frank Brighten, a British subject, residing at 45 Conduit Street, London, W. 1., England, have invented a new, original, and ornamental Design for a Bathing Cap, of which the following is a specification, reference being had to the accompanying drawing, forming part thereof.

In the drawing the three figures are:—

I claim:

The ornamental design for a bathing cap, as shown.

In testimony whereof I affix my signature.

FRANK BRIGHTEN.
